(57) **CLAIM**

The ornamental design for an intraocular lens insertion device, as shown and described.

DESCRIPTION

1. Intraocular lens insertion device

Figure 1.1 is a perspective view of an intraocular lens insertion device;

Figure 1.2 is a front view thereof;

Figure 1.3 is a back view thereof;

Figure 1.4 is a side view thereof;

Figure 1.5 is another side view thereof;

Figure 1.6 is a top view thereof;

Figure 1.7 is a bottom view thereof;

Figure 1.8 is a rear perspective view thereof; and

Figure 1.9 is another perspective view thereof.

The broken lines shown in Figures 1.2 and 1.3 illustrate portions of the intraocular lens insertion device that form no part of the claimed design.
